UNITED STATES PATENT OFFICE.

ELMER FLETCHER, OF CHICAGO, ILLINOIS, ASSIGNOR, BY DIRECT AND MESNE ASSIGNMENTS, TO FLETCHER-WICKES COMPANY, A CORPORATION OF ILLINOIS.

SOUND BOX.

1,427,198.

Specification of Letters Patent. Patented Aug. 29, 1922.

Application filed November 2, 1917. Serial No. 199,807.

To all whom it may concern:

Be it known that I, ELMER FLETCHER, a citizen of the United States, and a resident of Chicago, in the county of Cook and State 5 of Illinois, have invented certain new and useful Improvements in Sound Boxes, of which the following is a full, clear, and exact description.

The invention relates to sound boxes for 10 phonographs or recorders.

One object of the invention is to provide an improved sound box in which provision is made for deflecting the sound between the diaphragm and the tone-arm or sound-outlet, so that the sound will be diffused and amplified but also mellowed to eliminate the sharp metallic noises or sounds.

Another object of the invention is to provide an improved connection between the 20 needle-support and the sound-box, which is simple in construction and efficient in operation.

The invention consists in the several novel features hereinafter set forth and more particularly defined by claims at the conclusion 25 hereof.

In the drawings: Fig. 1 is a side elevation of a phonograph embodying the invention. Fig. 2 is a section taken on line 2—2 of 30 Fig. 1. Fig. 3 is a section taken on line 3—3 of Fig. 2. Fig. 4 is a detail perspective showing the parts of the improved pivotal connection between the needle support and the sound box.

The invention is shown as applied to a 35 reproducer instrument comprising a sound box 7 which is provided with a chamber 8 in which a diaphragm 9 is held in any suitable manner, as exemplified by the rubber-covered spring-ring 10 which holds the margin of the diaphragm seated on an elastic ring 11. A member 5 on the back of the sound box is formed with a boss 12 which serves as a sound-outlet and is adapted for 40 connection to a tone-arm 14.

A needle 15 is mounted on a support 16 which is preferably held on the sound-box as hereinafter more fully set forth, and is provided with a lug 17 to which the diaphragm operating arm 18' is secured as well 45 understood in the art.

A wall 18 integral with the sound-box is disposed in the sound-box and in back of the diaphragm 9. This wall has openings or

perforations 19 therethrough near the margin of the diaphragm. Wall 18 is also spaced from the diaphragm. The back-member 5 comprises a plate 6 which has its margin secured to the sound-box, by screws 22 and has its central portion spaced away 60 from wall 18, leaving a chamber 6a between said wall and plate-portion. The chamber 6a is in communication with the outlet 12 through openings 21 in the central portion of plate 6 of member 5, which extends across 65 the inner end of the sound outlet 12. As a result of this construction, the vibrations of the diaphragm, the amplitude of which is greatest at its center, do not pass directly from the center of the diaphragm to the outlet, but are deflected to pass outwardly and thence backwardly through the perforations 19 to the chamber in the back of the wall 18 and thence inwardly to and through the openings 21 into the outlet 12. In practice, 70 it has been found that this construction causes the sound to be amplified and mellowed so that the sharp metallic tones are effectively eliminated.

In practice it has been found that when 80 the openings 19 are spaced apart, and of the number and area shown, sound amplification occurs in the chamber between the diaphragm and wall 18, and said chamber is formed to permit this result to be attained. 85 By forming the wall 18 integral with the case the rigidity necessary for efficient conduction and amplification is attained.

The improved connection for the needle support comprises a pair of spring clips 90 24. The sound-box 7 is formed with a pair of lugs 25, each having a sharp edged rib 26 adapted to engage one of the grooves 27 adjacent the respective ends of the needle support. These ribs and grooves form a 95 knife-edged pivotal bearing for the needle support. Each clip 24 is provided with an inwardly extending arm or member 28 which is adapted to engage a hole 29 in the outer end of one of the lugs 25 and an inwardly extending arm 30 having an upturned inner terminal 31 which is adapted to engage a countersink or seat 32 in the underside of the needle support 16. Each clip 24 is formed of spring-wire so that the 100 support will be resiliently held by these clips in connected relation to the sound box. In practice, the arm 18' is usually fixed to the 105

diaphragm at the factory, so that in event replacement of a diaphragm is necessary, the needle-support must be removed with it. These spring clips permit the ready removal 5 and replacement of the diaphragm and needle support and also serve to hold the support resiliently in place, so that conduction of the vibrations from the needle to the arm and diaphragm will not be interfered with.

10 To release the support, it is only necessary to spring the arms 30 downwardly and then swing the clips laterally to clear the support. In replacing the support, the reverse operation of the clips will serve to quickly 15 connect the support to the sound box. This connection exemplifies one in which connecting screws are dispensed with and which can be produced at a low cost. In practice, it has also been found that this connection 20 results in efficient conduction of the vibrations to the diaphragm.

The invention is not to be understood as restricted to the details set forth, since these may be modified within the scope of the appended claims, without departing from the spirit and scope of the invention.

Having thus described the invention, what I claim as new and desire to secure by Letters Patent, is:

30 1. In a sound box, the combination of a case having a fixed back-wall provided with a centrally disposed outlet connection, a diaphragm in the box, operating means for the diaphragm, and an intermediate wall, integral with the case and spaced from the diaphragm and the back-wall, having its central portion imperforate and a series of openings adjacent its periphery disposed in entirety outwardly of the outlet connection 35 to prevent direct passage of any sound from the diaphragm into the outlet connection,

the diaphragm being insertable and removable through the front of the case.

2. In a sound box, the combination of a case having a back-wall provided with a centrally disposed tubular sound outlet connection, a diaphragm in the box, operating means for the diaphragm, and an intermediate wall in the case spaced from the back wall and from the diaphragm, having its central portion imperforate and having a series of openings, adjacent its periphery and disposed in entirety outwardly of the outlet connection to prevent direct passage of any sound from the diaphragm to the outlet connection, said openings being widely separated and fixed and sufficiently limited in area to cause amplification of the sound in the chamber between the plate and the back-wall, the outlet connection being provided with a fixed transverse wall having a series of openings therein formed to cause amplification of sound when it passes from the said chamber into the tubular outlet.

3. In a sound box, the combination of a case having a back wall provided with a centrally disposed sound outlet connection, a diaphragm in the case, operating means for the diaphragm, and an intermediate wall integral with the case, spaced from the back wall and from the diaphragm, having its central portion imperforate and having a series of openings adjacent its periphery and disposed in entirety outwardly of the outward connection to prevent direct passage of any sound from the diaphragm to the outlet connection, said openings being widely separated and fixed and sufficiently limited in area to cause amplification of the sound in the chamber between the plate and the back-wall.

ELMER FLETCHER.
